CLAIM

The ornamental design for a refuse container, as shown and described.

DESCRIPTION

FIG. 1 is a left side elevational view of a refuse container showing my new design;

FIG. 2 is a front elevational view thereof;

FIG. 3 is a top plan view thereof; and

FIG. 4 is a rear elevational view thereof.

The right side is a mirror image of the left side thereof.

The bottom is plain and unornamented.

*Fig. 1**Fig. 2**Fig. 3**Fig. 4*
